UNITED STATES PATENT OFFICE.

WILLIAM R. SMITH, OF BUFFALO, NEW YORK, ASSIGNOR TO BUFFALO LEATHER CO.,
OF BUFFALO, NEW YORK, A CORPORATION OF WEST VIRGINIA.

GAS-BURNER.

1,058,007.

Specification of Letters Patent.

Patented Apr. 1, 1913.

Application filed December 6, 1911. Serial No. 664,300.

To all whom it may concern:

Be it known that I, WILLIAM R. SMITH, a citizen of the United States, and a resident of Buffalo, in the county of Erie and State 5 of New York, have invented certain new and useful Improvements in Gas-Burners, of which the following is a specification.

This invention relates to gas burners for consuming acetylene or other illuminating 10 gas, and it has for its object to provide a burner adapted to emit a luminous flame in a highly heated chamber or inclosure where the temperature is so high that a satisfactory combustion cannot be produced by the use of 15 an ordinary gas burner.

My invention is embodied in a gas burner having means for supplying fresh relatively cool air to the external surface of the flame emitted by the burner, in sufficient quantity 20 to support or satisfy combustion, so that a luminous flame may be produced in a relatively hot inclosure.

Of the accompanying drawings which form a part of this specification,—Figure 1 25 represents a side elevation of a burner embodying my invention; Fig. 2 represents a section on line 2—2 of Fig. 1; Fig. 3 represents a top view of the burner; Fig. 4 represents a section through the pillar portion of 30 the burner, on line 4—4 of Fig. 2, removed from the casing portion; Fig. 5 represents a section through the casing portion on line 5—5 of Fig. 2, the pillar portion being removed; Fig. 6 represents a side view of the 35 burner tip.

Similar reference characters indicate the same parts in all the figures.

My improved burner is composed of a casing 12 having ears 13 adapted to be screwed 40 to a suitable support or holder. The casing 12 has an internal air chamber and a nipple 14 to which an air supply pipe may be attached. Said casing is provided with annular inwardly projecting seats 15, 16, forming, with the pillar 17 next described, an annular air chamber or passage 18 communicating with the nipple 14. The seats 15, 16 are tapered and adapted to have a tight frictional fit on tapered enlargements 45 19, 20, on the pillar 17. Said pillar is tubular and adapted to conduct gas, and has a

refractory tip 21, of any suitable material such as lava, the tip having a slit or gas outlet 22. The tip may be of any suitable construction adapted to burn acetylene or other 55 illuminating gas which is admitted through a branch or nipple 23 at the lower end of the pillar.

The upper seat 16 in the burner casing 12 is provided with a series of small grooves 60 24, Fig. 5, which constitute outlets adapted to deliver small jets of air upwardly against the outer surface of the gas flame burning at the tip 21. These air jets unite and form an annular jet surrounding the flame and supplying sufficient oxygen to satisfy combustion in a highly heated inclosure, so that a brilliant flame is insured.

The described burner is particularly useful for illuminating (as well as heating) the 70 interior of an oven employed for baking or vulcanizing patent leather. It is, of course, adapted for use in other heated inclosures.

I claim:—

1. An illuminating gas burner comprising 75 a chambered casing having annular seats at the top and bottom of the chamber and an air inlet between said seats, and a burner pillar closely fitting said seats and forming the inner wall of an annular air passage 80 communicating with said inlet, one of said seats being provided with a plurality of air outlets adapted to project jets of air upon the exterior of the gas flame.

2. An illuminating gas burner comprising 85 a casing having a chamber and provided with inwardly projecting annular tapering seats and with an air inlet between said seats, and a burner pillar having tapering enlargements closely fitting said seats and 90 forming the inner wall of an annular air chamber, air passages being formed between the pillar and one of said seats adapted to project jets of air upon the exterior of the gas flame. 95

In testimony whereof I have affixed my signature, in presence of two witnesses.

WILLIAM R. SMITH.
